UNITED STATES PATENT OFFICE.

EDWARD O. GOSS, OF WATERBURY, CONNECTICUT, ASSIGNOR TO
SCOVILL MANUFACTURING COMPANY, OF WATERBURY, CON-
NECTICUT, A CORPORATION OF CONNECTICUT.

CARTRIDGE-CLIP.

SPECIFICATION forming part of Letters Patent No. 770,497, dated September 20, 1904.

Application filed November 27, 1903. Serial No. 182,896. (No model.)

To all whom it may concern:

Be it known that I, EDWARD O. Goss, a citizen of the United States, residing at Waterbury, in the county of New Haven and State 5 of Connecticut, have invented a certain new and useful Improvement in Cartridge-Clips, of which the following is a full, clear, and exact description.

This invention relates to the holding device 10 used to temporarily support a number of metallic cartridges for insertion in a magazine-gum, and the device is specially designed for use in the new Springfield rifle of the United States government.

15 In the class of "clips" (as these holding devices are commonly called) in which a case is used having inwardly-projecting lips which coöperate with reversely-projecting tongues on the spring inserted in the case to hold the 20 spring in place in the case it happens that the tongues slip under the lips, and thus the spring has a longitudinal movement which tends to disarrange the cartridges.

The object of the present invention is to 25 provide against such displacement; and to this end the invention consists, specifically stated, in a clip the case of which has its lips made concave, so that while they project up into the case and path of movement of the spring's 30 tongues and serve to lock the spring in position they prevent the spring's tongues from passing beneath them, and so prevent any endwise movement of the spring after it is once snapped into position.

35 In the accompanying drawings, illustrating the invention, in the several figures of which like parts are similarly designated, Figure 1 is a perspective view of the clip. Fig. 2 is a perspective view of the case. Fig. 3 is a 40 perspective view of the spring. Fig. 4 is a longitudinal section of the clip. Fig. 5 is a transverse section in front of one of the lips.

The case 1 and spring 2 may be of any approved construction excepting as hereinafter 45 specified.

The case 1 has the lips 3 cut from its bottom 4 near opposite ends and projecting in opposite directions and concaved transversely from the upper side, so that while the free ends of these lips project above the level of 50 the bottom of the case the lower levels of the concave portions are practically on a line with the upper level of the bottom of the case, and hence while they serve to engage the free ends of the tongues 5 on the spring 2, and so 55 lock the spring to the case, they prevent said tongues from passing beneath them or between them and the bottom of the case, and thus immovably lock the spring in place, or, in other words, prevent the accidental and ob- 60 jectionable lengthwise movement of the spring relatively to the case, and so prevent disarrangement of the cartridges when placed in the clip.

While I prefer to concave the lips 3, and 65 thus make them the obstructing members, still these lips might be made straight and the tongues concaved, or both the lips and the tongues might be made concave or either of them concave and the other convex, or the 70 same obstructive result might be accomplished by otherwise deforming either or both elements.

What I claim is—

1. A cartridge-clip, comprising a case and 75 a spring having oppositely-projecting interlocking elements in the form of lips and tongues, one of these elements bent transversely to insure endwise engagement with the other element and preclude passing beyond the same, whereby relative longitudinal movement of the spring and case is prevented.

2. A cartridge-clip, having a case provided with oppositely-arranged upwardly-projecting transversely-concaved lips, and a spring 85 having tongues adapted to interlock with said lips.

3. A cartridge-clip, having a case provided with lips projecting inwardly from its bottom 90

and concaved transversely so as to bring their
lower levels substantially on a level with the
level of the bottom of the case, and a spring
having tongues adapted to engage such lips,
5 whereby the spring is held against longitudi-
nal movement in the case.
In testimony whereof I have hereunto set

my hand this 23d day of November, A. D.
1903.

EDWARD O. GOSS.
